ATTORNEY

UNITED STATES PATENT OFFICE.

FERDINAND STRASSWIMER, OF NEW YORK, N. Y.

NECKTIE.

Application filed January 28, 1925. Serial No. 4,653.

This invention relates to neckties, the invention having more particular reference to ready made ties.

The invention has for an object to provide a novel form of attaching means for ready made tie, that will facilitate the attachment and removal of the tie, while at the same time serving to hold the tie properly positioned on the collar.

For further comprehension of the invention, and of the objects and advantages thereof, reference will be had to the following description and accompanying drawing, and to the appended claim in which the various novel features of the invention are more particularly set forth.

Fig. 1 of the drawing is a face view showing my improved tie as in place on a collar, the latter being shown in dot and dash lines.

Fig. 2 is a horizontal sectional view showing a modified form of the collar.

Fig. 3 is a fragmentary rear view of a tie showing a further modification.

Fig. 4 is a vertical sectional view of the tie shown in Fig. 3.

My improved tie is constructed to have the appearance of a four in hand tie, consisting of the upper element 10 and the depending ends 11, which may be formed in any suitable manner and from any suitable material. To the back of this top portion 10 of the tie I attach an improved means for mounting the tie on the collar. As shown in Fig. 1 a band 12 of cloth or like material is passed through a suitable slot or slit formed in the said back portion of the element 10. This band 12 is of a length so that the ends thereof will be adequately covered by the wings 14 of the collar, and is provided at opposite ends with hooks 15. To facilitate fastening of the tie in place on the collar the tie may be secured to the band 12 nearer one end than the other, the short end of the band being secured last in place. To secure the band in place I provide holes 18 in the inner fold 19 of the collar, into which the hooks

15 engage. The tie, when in place, is held properly positioned, and has all the appearance of an accurately made four in hand tie, while it is both cheaper to construct and more readily attached.

Instead of providing hooks on the end of the band 12 I may form the end of the latter with buttonholes and attach buttons 20 on the inner fold 19 of the collar, as shown in Fig. 2 of the drawing.

In the form of the invention shown in Figs. 3 and 4 the band 12^b has a central insert 25 of relatively stiff and unyielding elastic material that engages in the slit in the back of the tie. Embedded in this insert, and extending from side to side thereof, are wires 26 that have outturned ends 27 projecting from opposite sides of the insert. These wires are spaced from one another a distance equal to the width of the back loop 28 in the tie proper formed by the slot that receives the tie band, so that when the band is in place it is secured to the tie, to prevent longitudinal slipping thereof, by means of the ends of the wires 27. The tie band being also provided with pointed pins or spikes 29 engaging the rear portion 28 of the tie.

Having thus described my invention what I claim as new and desire to protect by Letters Patent of the United States is as follows:

The combination, in a necktie having a knot element and provided with slits in the back portion thereof, of a supporting band provided with a central insert of stiff material, passing through said slits and being formed with a plurality of projecting pointed pins engaging said back portion to hold the tie in position on said band, supplemented by wires embedded in said central insert, and having out-turned extended ends to abut against the outer edges of the back loop formed by the said slit.

In testimony whereof I have affixed my signature.

FERDINAND STRASSWIMER.
